OIL WELL TOOL JAR

Filed May 9, 1928

INVENTOR:-
EARL S. HARTSON.
By Martin P. Smith, Atty.

UNITED STATES PATENT OFFICE.

EARL S. HARTSON, OF LOS ANGELES, CALIFORNIA.

OIL-WELL-TOOL JAR.

Application filed May 9, 1928. Serial No. 276,412.

My invention relates generally to deep well drilling apparatus and more particularly to an oil well tool jar, that is a device that may be utilized for jarring or hammering a drill bit or like tool in the event that the same becomes stuck during well drilling operations, and the principal objects of my invention are to generally improve upon and simplify the construction of the existing forms of oil well tool jars and to provide a device of the character referred to that is relatively simple in construction, inexpensive to manufacture, capable of being readily assembled or taken apart, and which is strong and durable in construction so as to effectively withstand the heavy strains and rough usage to which the tool is subjected.

With the foregoing and other objects in view, my invention consists in certain novel features of construction and arrangement of parts that will hereinafter be more fully described and claimed and illustrated in the accompanying drawing, in which—

Fig. 1 is a vertical section taken lengthwise through the center of the oil well tool jar embodying the principles of my invention.

Fig. 2 is an enlarged horizontal section taken on the line 2—2 of Fig. 1.

Fig. 3 is a horizontal section taken on the line 3—3 of Fig. 1.

Fig. 4 is a horizontal section taken on the line 4—4 of Fig. 1.

Fig. 5 is a horizontal section taken on the line 5—5 of Fig. 1.

Referring by numerals to the accompanying drawings which illustrate a practical embodiment of my invention, 10 designates the upper member of the body of the jar, which upper member is substantially cylindrical in form and provided with an axially disposed circulation duct 11. The upper portion of the member 10 is externally threaded as designated by 12 in order that it may be detachably connected to the lower portion of the drill stem, and the lower portion of member 10 is externally threaded in order that it may be screwed into the internally threaded upper portion of the intermediate member 13 of the body of the tool and which intermediate member has the same external diameter as the upper member 10.

The lower portion of the intermediate member 13 is internally threaded so as to receive the threaded pin 14 on the upper end

of the lower member 15 of the body of the tool, and which lower member has the same external diameter as the upper member 10 and intermediate member 13.

Extending axially through the intermediate member 13, the lower member 15 and the external pin that depends from the upper member 10, is a tubular mandrel 16, the lower end of which is externally threaded as 60 designated by 17 in order that it may be screwed into the box of a well drilling tool.

Arranged to slide freely upon the upper portion of the mandrel 16 is a sleeve 18 which performs the functions of a jar or 70 hammer and formed integral with the upper end of this sleeve is a circumferential flange 19 that is adapted to move vertically within a cylindrical chamber 20 that is formed in the threaded stem that depends from the upper member 10, and said chamber extending a short distance downwardly in the upper portion of intermediate member 13.

Formed in the upper portion of the mandrel 16 is a circumferential groove 21 and formed through the upper portion of the jar or hammer 18 is a diametrically arranged slot 22 within which is arranged for sliding movement a latching plate 23 in which is formed a short longitudinally disposed slot 85 24 of sufficient size to permit the passage of the mandrel 16.

Secured in any suitable manner to the outer face of sleeve 18 a short distance below the slot 22 and plate 23 that operates 90 therein, is the lower end of a flat spring 25, the upper free end of which bears against the rear end of the latching plate.

The forward lower corner of the latching plate 23 is rounded or beveled as designated 95 by 26 in order that it will engage and ride past the shoulder 27 that is formed in intermediate member 13 at the lower end of the chamber 20.

Formed through the intermediate member 100 13 and through the pin 14 that projects upward from the lower member 15 is a chamber 28 through which the jar or hammer is adapted to slide and arranged within this chamber and surrounding the tubular mandrel is a relatively stiff expansion spring 29, the upper end of which bears against the lower end of the jar or hammer 18 and the lower end of said spring rests on the bottom of the chamber 28.

Formed within the lower member 15 and communicating with the opening there-

through that is occupied by the mandrel 16 is a plurality of longitudinally disposed slots 30 provided at their upper ends with abrupt shoulders 31 and at their lower ends 5 with shoulders 32, and projecting into these slots are lugs 33 that are formed integral with the lower portion of the mandrel 16.

In order that the lower portion of the mandrel bearing the lugs 33 may be assembled 10 within the lower member 15 of the body of the tool said lower member is preferably formed in two parts that are connected by means of a welded joint.

In the use of my improved jar the body 15 thereof is connected to the lower end of a drill stem by screwing the pin that projects from the upper end of member 10 into the box at the lower end of said drill stem and the tool is now lowered into the well hole 20 and the threaded lower end of the mandrel is screwed into the box of the tool that is stuck or anchored in the formation at the bottom of the well hole.

It will be understood that when the tool 25 is made ready for use the latch plate 23 is moved to its forward limit of movement under the influence of the spring 25 and when so positioned that portion of the latch plate to the rear of slot 24 engages in the groove 30 21 in the mandrel, thereby locking the jar or hammer 18 to said mandrel.

After the mandrel has been connected to the upper end of the tool that is stuck or anchored, the drill pipe to which the body of 35 the jar is connected is drawn upward, and during such movement the mandrel 16 and the jar or hammer 18 remain stationary and spring 29 which bears against the lower end of the jar or hammer will be compressed and 40 therefore put under tension.

When the body of the tool has been drawn upward to a point where the shoulders 32 at the lower end of the slot 30 engage the under faces of lugs 33 the shoulder 27 at the 45 lower end of chamber 20 will bear against the lower rounded corner 26 at the forward end of latch plate 23, thereby moving said latch plate a slight distance rearwardly against the resistance offered by spring 25 50 and as that portion of the latch plate to the rear of slot 24 passes out of groove 21, spring 29 will act to instantly move the hammer 18 upwardly with considerable force and the upper end thereof carrying the flange 19 55 will strike against the shoulder at the upper end of chamber 20 and the force of this blow will be transmitted through the body of the tool to the lugs 33 by the shoulders 32 that are in engagement with said lugs 60 and thus an upward force tending to dislodge the stuck tool will be exerted on the mandrel that is connected to said tool.

The drill tube and body of the tool are now lowered with a quick movement and 65 the force produced by the weight of the drill

tube will be transmitted from the body of the tool through the shoulders 31 on to the tops of the lugs 33, thereby producing a driving blow upon the mandrel that is connected to the stuck tool.

The operations just described are repeated and as a result the force of the developed 70 blows is transmitted to the mandrel and tool first in an upward direction and then in a downward direction, and which action will 75 be effective in releasing the stuck or anchored tool.

It will be understood that when the drill pipe and tool are lowered to produce a downward blow upon the mandrel as just 80 described, the latch plate 23 will be moved forward under the influence of spring 25 so as to re-engage in the groove 21 and lock the hammer to the mandrel, which action occurs when the groove 21 aligns with the 85 slot 22 that is occupied by the latch plate.

Thus it will be seen that I have provided an oil well tool jar that is relatively simple in construction, inexpensive to manufacture, and very effective for performing the 90 functions for which it is intended.

It will be understood that minor changes in the size, form and construction of the various parts of my improved oil well tool jar 95 may be made and substituted for those herein shown and described without departing from the spirit of my invention, the scope of which is set forth in the appended claims.

I claim as my invention:

1. In an oil well tool jar, a cylindrical 100 body adapted to be connected to the lower end of a drill tube, a mandrel arranged for sliding movement within said cylindrical body, cooperating shoulders formed on said mandrel and cylindrical body, a tubular 105 hammer arranged for sliding movement on the upper portion of said mandrel, an expansive spring arranged beneath said hammer, and means for latching the hammer to said mandrel during the upward movement 110 of the cylindrical body relative to said mandrel.

2. In an oil well tool jar, a cylindrical 115 body adapted to be connected to the lower end of a drill tube, a mandrel arranged for sliding movement within said cylindrical body, cooperating shoulders formed on said mandrel and cylindrical body, a tubular 120 hammer arranged for sliding movement on the upper portion of said mandrel, an expansive spring arranged beneath said hammer, means for latching the hammer to said mandrel during the upward movement of the cylindrical body relative to said mandrel, and means for releasing said latching means 125 to permit the upward travel of the hammer under the influence of said spring.

3. In an oil well tool jar, a cylindrical 130 body, a tubular mandrel axially arranged within said body, lugs on said tubular man-

drel, slots arranged within said body for the accommodation of said lugs, a spring pressed tubular hammer arranged for sliding movement upon said mandrel within said body, 5 and means for locking said hammer to said mandrel during the upward movement of the cylindrical body relative to said mandrel.

4. In an oil well tool jar, a cylindrical body, a tubular mandrel axially arranged 10 within said body, lugs on said tubular mandrel, slots arranged within said body for

the accommodation of said lugs, a spring pressed tubular hammer arranged for sliding movement upon said mandrel within said body, means for locking said hammer 15 to said mandrel during the upward movement of the cylindrical body relative to said mandrel, and cooperting shoulders on said hammer and cylinder body.

In testimony whereof I affix my signature.

EARL S. HARTSON.
